UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE SYSTEM.

1,107,144.

Specification of Letters Patent. Patented Aug. 11, 1914.

Application filed March 30, 1906. Serial No. 309,010.

To all whom it may concern:

Be it known that I, EDWARD E. CLEMENT, a citizen of the United States, residing at Washington, District of Columbia, have invented certain new and useful Improvements in Telephone Systems, of which the following is a specification, reference being had therein to the accompanying drawing.

My invention relates to telephone exchange systems, and particularly to those in which a combination of manual and automatic devices is employed for the purpose of interconnecting subscribers. Briefly stated, the system of my present invention comprises subscribers' lines terminating on answering-jacks, and having multiples in automatic connector switches. Each connector switch contains the multiple-contacts of a number of lines, preferably one hundred, and the circuit or trunk leading from each switch is carried to multiple-jacks located in front of the several operators. Each operator is provided with a number of pairs of connecting plugs and cords and with signal controlling devices whereby the automatic connector switches may be controlled.

In operation, a subscriber calls and thereby sets a signal in front of the operator, who plugs in with her answering-plug and connects her telephone to the cord by means of an automatic listening key or listening relay as shown, and ascertains the number of the subscriber wanted. Having ascertained this number, she inserts the companion plug into a trunk-jack connected to a connector switch containing the terminals of the desired line. She then sets up on her transmitting device associated with that pair of plugs the number of the line in the connector group, together with the number of the station on the line, if it be a party-line. She then turns to other work, and pays no further attention to the connection until at the close of the conversation, her disconnect or clearing-out signal is exhibited, when she pulls down the plugs. When the operator has set up the sending device, which preferably consists of a set of push-button keys bearing the numbers to which they correspond, she connects the cord-circuit thereby to a common power-driven commutating device, by which the desired selecting impulses are placed upon the trunk in proper sequence. The switch I prefer to

employ is a two-motion spindle switch having its contacts either in vertical rows or horizontal rows, and arranged in decimal relation, that is to say one hundred contacts in ten sub-divisions of ten contacts each. The 60 arrangements and circuits of this switch will not be made the subjects of claims in the present case. The only mechanical movements in the switch are the two movements of its spindle to select the contacts of the 65 line wanted; all the various changes required being produced by relays. In order to select an idle trunk, the operator tests the multiple-jacks of the particular hundred desired, preferably by sliding her 70 plug tip along the row, as usual in similar tests at present. By this arrangement I have only to select two digits in any switch, in order to find a line wanted. For example, suppose the number called for is 4468. The 75 operator tests and plugs into an idle trunk-jack in the group numbered 44, and sets up the buttons of the signal sender for the number 68. She sets also an additional button to determine the station required upon the 80 line indicated. I provide selector relays which respond to the party-line impulses to apply the proper generator connections to the line, and I also provide an automatic controlling device which rings the subscriber 85 at the proper intervals, until he answers. When the subscriber answers, the generator is cut off and the talking circuit established.

In the system I have illustrated and shall describe in connection herewith, I employ a 90 common battery at the central office, and what is known as harmonic ringing. It will be understood, however, that other systems and other circuits may be employed without departing from the spirit of my invention. 95

The invention is illustrated in the accompanying drawings, in which—

Figure 1 is a diagram of a subscriber's station and an operator's cord-circuit, with a trunk-terminal adapted to work therewith. 100 Fig. 2 is a diagram of one form of a sending device and the keys which I may employ. Fig. 3 is a diagram of the connector switch employed. These three diagrams are so arranged that they may be put together and form one complete diagram of the system. 105

Referring to the drawings and particularly to Fig. 1, A is a subscriber's station having the usual subscriber's common battery outfit, consisting of transmitter, re- 110

- ceiver; switch-hook, ringer and condenser. From this substation the line-wires 1—2 extend to the central office, where they pass through the contacts of the cut-off relay, M' , which normally connects them to the line-relay M and ground, respectively. The line relay is connected on the other side to the main battery, B , and controls a signal lamp, L , associated with the answering-jack, J .
- 10 The answering-jacks, J , are supposed to be grouped in a convenient manner, together with their signal lamps, L , in front of the operators, and when any line is calling it is intended that it shall be connected through a trunk-jack, J' , with a trunk-line leading to an automatic switch, S , (see Fig. 3), by which the subscriber wanted can be directly reached.
- In order to interconnect the line and trunk-jacks I provide a pair of plugs, P , P' , having their tips and sleeves respectively connected through the conductors 3—5 and 4—6, these conductors being interrupted for direct currents by the condensers, C . The answering plug, P , has associated with it a supervisory signaling lamp, L' , directly controlled by the tip relay, R , which responds to current in the subscriber's line as long as the plug is in a jack; the lamp is also indirectly controlled by the sleeve relay, R' , which puts battery on the armature of the tip relay when the plug is first inserted. Current through the sleeve relay is also necessary in order to energize the cut-off relay, M' , of the line in making connection therewith. The calling plug, P' , has three contacts, which I may call the tip, p , the ring, p' , and the sleeve, p'' , the ring in this case corresponding to the sleeve of the plug, P .
- 20 When the plug is inserted in a trunk-jack, J' , the tip and ring come into connection respectively with the jack springs, j , j' , while the sleeve, p'' , comes into contact with a thimble, j'' , connected through a resistance, j'' , to ground. This thimble is for test and also to furnish a circuit for the cord cut-off relay, R^2 . There are two relays, R^2 , R^3 , associated together for controlling the connection of the operator's telephone. The relay, R^8 , takes current through the wires 17 and 18 when the plug, P , is first inserted in answer to a call, the circuit— B , 19, 17, 18 and ground being then immediately closed by the relay, R' , pulling up. Thereupon the relay, R^3 , immediately pulls up, the relay, R^2 , which also controls it remaining quiescent. In so pulling up it closes the two sides of the operator's secondary circuit —9—10— onto the bridge wires 7—8 across the cord-conductors 3—4. This secondary circuit contains the operator's receiver T' , and the secondary winding, i , of the induction coil, I . The primary, i' is included in a short-circuit 13—14 with the condenser, C' , and the transmitter, T , the latter deriv-

ing its current supply direct from the main battery through the choke-coil, i^3 by the circuit— B , 20, 21, 22 and ground. The tertiary winding, i^2 , is included in the test circuit 11—12, which passes from ground through a back contact on the relay, R^2 , to the tip conductor 5 and so to the tip of the calling plug, P' .

The trunk-lines 23—24 which terminate in the jacks, J' , are each multiplied to all the sections of the switchboard, so that any operator can reach any trunk. The trunks are arranged in groups, those of each group leading to similar switches in which the same group of subscribers' line-wires are multiplied. This is necessary so as to always have enough idle trunks and switches to reach a number of subscribers of the same group at the same time. Each connector switch is supposed to contain the terminals of one hundred lines, and as a fair average I may assign ten switches to each one hundred lines, so as to be able to call ten subscribers out of that particular hundred at the same time. All of these subscribers' lines are multiplied into the ten switches, and the ten trunks from the ten switches are carried together to the switchboard, where they are multiplied and have their jacks appear together in a group on all the switchboard sections. These jacks may be arranged in a continuous line either vertically or horizontally, so that in testing to find an idle trunk, the operator will simply run the tip of her plug down the row in the group desired. 100 These groups are numbered from 0 to 99, which means that through the trunks of No. 0 group the subscribers' lines whose numbers are from 0 to 99 can be reached; through No. 1 group those whose numbers are from 100 to 199 can be reached; through No. 2 group those whose numbers are from 200 to 299 can be reached, and so on up to 9999, or if it be desired to carry it so far, even to 99,999, which would of course require 10,000 110 multiple jacks per section of three operators' positions, which is the same as in a ten thousand multiple-board now. In other words, the same multiple-board which now serves 10,000 subscribers can be cut over by 115 my present invention to accommodate 100,000 subscribers, at least so far as regards the multiples. In actually reconstructing such a board, it would be necessary to increase the number of answering-jacks, and also of cords and plugs since the operators will handle a great many more calls than before.

In answering a call and making the connection the operator proceeds as follows: 125 Seeing the lamp, L , light, she inserts plug, P , into the corresponding jack, J , whereupon the battery, B , sends current at once through the sleeve relay, R' , and the cord-conductor 4 to the line-extension 25, to the 130

cut-off relay M' and ground. The cut-off relay thereupon pulls up, putting the line-wires 1—2 onto their extensions 26 and 25 and thence onto the cord-conductors 3 and 4, whereupon relay R pulls up and opens the conductor leading to the lamp L' which had just been closed by the relay R' , the entire action being too quick for the lamp to have time to light. At the same time, relay R^2 10 pulls up and the operator's set, O , is bridged across the answering cord, while the test wire 11—12 remains connected to the tip of the calling plug. The operator picks up the plug P' and at the same time asks "Number"? Ascertaining the number, she tests with the plug, P' , the trunk-jacks corresponding to the hundreds of the line wanted, by running the tip, p , along the row of thimbles, j^2 , until she no longer gets a click. If 15 any trunk is busy, having a plug in it, the potential of its jack thimbles, j^2 , will be raised by main battery B , through the circuit—19, 27, 28 and the relay R^2 . Hence the tip of the testing plug will take current 20 off of this through the conductors, 5, 12 and 11 to the testing operator's tertiary winding, j^2 , this producing a click in the receiver, T' , each time the tip, p , passes over a charged or busy thimble. Having reached a jack 25 which produces no click, the operator puts in the plug, P' . Relay R^2 pulls up, the operator's telephone is disconnected and the test circuit of that plug is broken.

This much of the operation is substantially the same as in any manual system, substituting trunk-jacks for line-multiples, of course. The balance of the operation, however, is entirely different. The trunk 23—24 shown in the diagram, leads to the 30 connector switch, S , shown in Fig. 3, and this switch is operated by means of impulses over the two sides of the trunk, in a manner which is generally familiar to those acquainted with the art. In order to do this 35 I provide the operators with impulse transmitters or "senders". These devices I term multiple signal senders. The term multiple applies first because the device has the power to produce and send simultaneously 40 a plurality of series of signal impulses; and second because in each cycle of operation of the device these series of impulses are each produced a plurality of times. It will be obvious from the following disclosure of the 45 operation of this device that in each cycle of the multiple signal sender the conditions of proper electrical potential for a plurality of simultaneous series of impulses and for the repetition of each of these series of impulses 50 are produced upon the leading out wires or bus wires, whence by the proper provision of path for current through auxiliary signal selecting means, current impulses may be taken corresponding to any 55 one of the series of potential impulses of the

signal sender, or corresponding to a plurality of such series. For convenience I will first describe this arrangement as it is shown in Fig. 2, and will then proceed to point out its effect upon the apparatus of Fig. 3. In 70 this figure, Q^0 , Q , Q' , Q^2 , Q^3 , Q^4 , Q^5 , etc., are a set of wheels mounted on and turning with a common shaft, which may be driven in any suitable manner. The wheel, Q^0 , puts battery and ground alternately on the wire 75 29, which for purposes of illustration represents the metallic shaft connection between the wheels. The wheel Q is insulated from the shaft, is grounded, has an insulating spot in its periphery and controls by means of this spot the locking and unlocking wires 80 30 and 31, in a manner which will appear from the statement of operation. The wheels, Q' , Q^2 , Q^3 , Q^4 , etc., are number-wheels, the first one having one tooth, the second two teeth and so on up to ten teeth. (For simplicity of illustration only five wheels are shown). Around these wheels are three sets of pens, connected to the three 85 sets of keys, K' , K^2 , K^3 . As the wheels revolve from the position in which they are shown in the figure, they first make contact with the upper pens, q' , then with the pens, q^2 , then with those, q^3 . Thus the various control circuits governed by the keys and including the wheel contacts are independently and differently electrically characterized. The first set with their buttons or keys, K' , transmit the tens digit of any number, the next set transmit the units digit, and the 90 third set transmit the ringing number. All this will appear more clearly from the statement of operation.

The keys, K' , K^2 , K^3 are of the so-called self-latching selective ringing type now in common use on manual switchboards, and employ the principle shown in the patent to Ham, No. 605097 granted June 7, 1898. When any key is pressed down it pushes back the latch and releases the one that was 100 previously down, then latching itself. It will be noted that the bank of keys is divided into three sets or rows, K' , K^2 and K^3 respectively. The rows are each provided with the latching device of Ham, cited, the 105 rows being independent of each other in this respect; thus one key and only one of each row will remain depressed, the previously depressed key of each row being released by the depression of any other. In a 110 bank or row of keys of this nature, a key is depressed through a travel carrying it beyond the locking point; upon release it returns a very short distance and remains 115 locked there until released by the depression of the next key used. I take advantage of this detail in the row of keys K^3 in the following manner: The pairs of springs as 120 z^4 are to remain locked when the key is pressed, as described later, but the triple 125

springs k^6 are springs requiring but a momentary contact to energize primarily the pair of locking relays R^4 R^5 . To secure the desired end, I so gage the relation of the springs k^6 to the push button of the key that they are closed by the button when at its point of farthest travel but are released by the slight return travel of the button before it is locked. The springs k^4 however remain closed until the button is unlocked and fully released. Each set of keys has a common wire, this for the sets K' , K^3 being marked 32, these two being joined together and carried to a back contact of the relay R^4 , while that for the set, K^2 , is marked 33 and carried to another back contact of the same relay. The numbers to be sent are set up by depressing the keys, one of each row, the key of row K^3 being depressed last, and the act of depressing that key serving to energize and lock the relays R^4 R^5 , and then the signal is started at the beginning of a rotation of the shaft, when the first tooth of each wheel is about to strike its pen, q' , by the relay, R^4 , being deenergized, while the relay, R^5 , remains energized. The means of this is in the arrangement of the spring pens, q^5 , q^6 , on the wheel, Q . This wheel is rotated with the others in the direction of the arrow, and its insulating spot passes first under the spring pen, q^5 , momentarily cutting ground off of that and the wire 31, then subsequently under the pen, q^6 , taking ground off of that.

In calling the number wanted, which we will assume to be 4432-3, the operator plugs into a jack of No. 44 group, then presses down button No. 3 of the set, K' ; No. 2 of the set, K^2 , and No. 3 of the set, K^3 . The buttons of the sets, K' and K^2 have their several individual wires connected to the springs or pens q' , q^2 , on the several individual wheels, Q' , Q^2 , etc., and the effect of pressing down the buttons as mentioned is to connect the pen q' of the wheel Q^3 through the springs k' of the button k to the wire 32. At the same time the pin, q^2 , of the wheel, Q^2 , is connected through the springs, k^3 , of the button k^2 to the wire 33 and the spring, q^3 , of wheel, Q^3 , is connected through the springs, k^4 of the button, k^3 , to the wire 32. The set of buttons, K^3 , also have the starting springs, k^6 . This set of buttons being the last, or ringing set, the number is ready for transmission when any one of them is depressed, hence any one of these buttons not only finishes setting up the number, but by closing the springs, k^6 , puts ground momentarily on the starting wires 37 and 38, which pass to the two relays, R^4 , R^5 , respectively, and thence through the common return wire 39 to battery B and ground. Both the relays pull up, and both lock, the locking circuit of the relay, R^4 , being as follows: B, 39, R^4 , r^5 , 30, q^6 , Q and ground. The lock-

ing circuit of R^5 is as follows: B, 39, R^5 , r^7 , 31, q^5 , Q and ground.

Having thus set up the signal and put it in condition to be started at the beginning of a revolution of the main shaft, and having also plugged into the necessary hundreds group, the operator's work is finished. She pays no further attention to the connection until the subscribers have completed their conversation and have hung up, whereupon the relay, R , in Fig. 1 lets go, and the lamp, L' lights to call for disconnection. The operator then pulls the plugs.

The signal having been set up as described, the apparatus of Fig. 2 then operates as follows: The wheel, Q , in revolving will bring the insulating spot under the pen, q^5 , at first, and might thereby cut off the relay, R^5 , prematurely, but this is provided for by making a branch locking circuit 310 which is controlled through a contact of the armature, r^6 , and a ground wire 36 of the starting relay R^4 . Hence, as long as the relay, R^4 , is energized, the relay, R^5 , cannot be affected. Moreover, it will be observed that the wires 32 and 33 remain disconnected from the wires 15-16 until the relay R^5 is energized, while the relay, R^4 is deenergized. This condition is brought about when the insulating spot reaches the pen, q^6 . The relay R^4 , then lets go, and we have a continuous circuit from wire 32 as follows: 32, r' , 34, r^3 , 16, 5 (in Fig. 1), and to trunk-wire 23. We also have a circuit for wire 33 as follows: 33, r^2 , 35, r^4 , 15, 6 (Fig. 1) and the other trunk-wire 24. The insulating spot reaches the pen, q^6 , just before the first tooth on each wheel reaches its pen, q' ; hence as soon as the above desired condition is attained, the set of impulses which has been determined by the key, k , of the set, K' , comes from battery through wheel Q^0 and wire 29 through commutator and key and thence over the wire 32 to the wire 16 and so on to the wire 23 of the trunk, through which it passes into Fig. 3 to the relay, R^6 , which will be presently described, and which I shall call for convenience the vertical relay. At the end of this group of impulses, the teeth on the wheels will have gotten around to the pens, q^2 , and so the next group of impulses determined by the key, k^2 , will pass from ground through the wheel Q^0 and wire 29 through commutator and key and thence onto the wire 33 and so to the wire 15 and the trunk-wire 24, through which they reach the relay, R^7 , in Fig. 3, which will also be presently described and which I shall for convenience call the rotary relay. The names of these two relays are quite accurate in this system, because the relay R^6 does really produce a vertical motion of the switch S , while the relay R^7 produces a rotary motion thereof. At the end of this second group of impulses, the teeth on the

wheels have gotten around to the third set of pens, q^2 , and the impulses determined by the key, k^5 , then come from battery through wheel Q^9 and wire 29 through commutator 5 and key and thence through the wire 32 onto the wire 16 and so again to the trunk-wire 23 and to the vertical relay, R^6 . After this, the insulating spot on the wheel, Q , reaches the spring, q^5 , and momentarily cuts 10 off the ground therefrom. Since the relay, R^4 , is already deenergized, this breaks the locking circuit of the relay, R^6 , and it lets go, disconnecting the wires 15—16 from the wires 35—34, and leaving the apparatus free 15 from the talking wires 23—24 of the trunk.

It may be stated here that each cord pair is equipped with a pair of relays R^4 — R^5 and a bank of keys K^1 — K^2 — K^3 individual to that cord pair, but that the commutator 20 shaft and its series of wheels is common to all cord pairs and connectors in the entire exchange.

Referring now to Fig. 3, I will briefly describe the switch operation. The switch, 25 S , is shown only in diagram, but in so far as its mechanical features are concerned it is of the type shown in the following patents: Keith and Erickson, 815,176, and 815,321, granted March 13, 1906. The circuits I employ in the present case are entirely different from those of these patents, but the mechanical structure is so far the same that I employ a vertical spindle, s , which carries wipers, s' , to coöperate with 30 the line-terminals, s^2 , (see Fig. 1) or line-multiples, in the switch-banks; the switch spindle is set up step by step by the vertical magnet, s^3 ; and is rotated step by step by the rotary magnet, s^4 , controlled respectively by the relays, R^6 and R^7 . There 35 are supposed to be one hundred pairs of line-terminals in the switch-banks, and I do not require any separable test terminals, since I test directly on the tip side of the line 40 for a ground. The switch spindle controls a pair of springs, s^5 , which it opens when it is down in its normal position of disuse, for restoring purposes, as will presently appear. s^6 is the release magnet of the switch, which 45 when energized removes the detent pawls from the respective ratchets of the spindle, s , allowing the spindle to drop down and rotate back to zero, as fully described in the 50 patents referred to. This release magnet is 55 under the control of the relay, R^{10} , which in turn is controlled by the relays, R^6 and R^7 . It is also under the control of the test relay, R^{11} . R^{12} is a ringing-selector control relay, R^{13} is a trunk cut-off relay and R^{14} is a 60 ringing relay controlled by the commutator, X , which is common to the entire exchange, and is mounted upon the shaft carrying the wheels Q^9 , Q , Q' , etc. of Fig. 2, or is 65 mounted to revolve in synchronism with that shaft and its commutator wheels. R^{15}

is a slow acting relay, preferably a solenoid, which connects the test relay, R^{11} , at the moment of effecting connection, as controlled by the first ringing impulse, and at the same time opens the generator circuit, 40—41, 70 while the proper current is being selected. R^{16} to R^{21} , inclusive, are selective relays for enabling one or the other of the ringing generators, G , G' , G^2 and G^3 , to be connected onto the ringing contacts of the ringing relay, R^{14} , the particular generator being determined by the number of impulses received through the ringing-selector control relay, R^{12} , which operates the relays, R^{16} , R^{19} , R^{20} , R^{17} , R^{21} , R^{18} , or as many of them 80 as are desired, in succession, each of them locking as it operates.

The operation of this trunk scheme is as follows: In selecting the number we have assumed 4432-3; the trunk itself corresponds 85 to the number 44, so we have first three battery impulses coming over the wire 23, to the relay, R^6 , followed by two ground impulses over the wire 24 to the relay R^7 , and then three battery impulses again over the wire 23 to the relay, R^6 . The first three battery 90 impulses coming over the wire 23 cause the relay R^6 to pull up three times, each time closing the following circuit: B, 42, 43, 44, s^2 , 45, 46, 47, and ground to battery. The 95 vertical magnet, s^3 , steps the spindle, s , of the switch up three steps, so that the wipers, s' , stand opposite the third row of contacts. Two ground impulses then come over wire 24, affecting the relay, R^7 , which pulls up 100 twice, the first time closing the following circuit: B, 42, 48, R^9 , 49, 50, armature of R^{10} , 51 to ground and to battery. The relay, R^9 , instantly pulls up, cutting off the vertical magnet, s^3 , and locking itself by the following path: B, 42, 48, R^9 , r^9 , 52, 50, 51 and ground back to battery. The vertical magnet, s^3 , is therefore cut off for the rest of the transmission. The rotary magnet, s^4 , however, gets current each time the relay, R^7 , is 110 energized, over the following path: B, 42, 43, 44, s^4 , 53, 54, 55 and ground back to battery. The rotary magnet, s^4 , turns the spindle, s , two steps, so that the wipers s' , rest on the second pair of contacts in the third row, or 115 No. 32. Three battery impulses now come over the wire 23, causing the relay, R^6 , again to pull up three times. Each time it closes the following local circuit: B, 42, 56, R^{12} , 57, 46, 47, and ground back to battery. As a 120 branch of this same circuit, the wire 58 comes in from battery wire 42 through the solenoid R^{15} and goes to 57, 46, 47 and ground.

At this point in the development of the 125 connection immediately following the closure of the contacts of relay R^6 at the beginning of the first generator-selection impulse, two things occur simultaneously: (1) The solenoid R^{15} at 126

tracts its core opening the wires 40—41 and closing the switch 62 whereby a test circuit is formed through elements B, 42, 62, R¹¹, 63 to upper s', which at this moment is resting in contact with the line selected through the agency of vertical and rotary magnets s³ s⁴. If the line be busy then a circuit will exist from upper wiper s' to the tip of the plug and through the relay R to ground in case the line tested has called, or to another wiper s' and thence through a trunking equipment following the path through contact of R¹⁴, contact of R¹³, conductor 23 and winding of R⁶ to ground if that line has been called; in either case the test relay R¹¹ will be energized and in turn will energize the release magnet s⁶. If, however, the selected line with which the test wiper rests in contact is not busy no circuit will exist from that test wiper to ground and the test relay R¹¹ will not be energized; a branch path for the conductor 63 exists through the talking conductor of the trunk to the left hand contact of relay R¹⁴ and thence to an armature contact of relay R¹³ where it terminates open, but subsequent to the energization of relay R¹⁴ as about to be described, this branch path passes to the inner contact of the left-hand armature of that relay and thence over the conductor 41 to the right hand switch of the solenoid R¹⁵ which during the test period is open, and thus test relay R¹¹ has its circuit open at all points and the design of the device as a whole is that no energization of that relay may result when the line selected is in a condition of disuse and subject to use in the connection now being established. (2) The relay R¹² is energized over the path B, 42, 56, R¹², 57, 46, 47 and ground. By the closure of the left-hand armature of relay R¹², circuit is formed through elements B, 42, 56, 59, armature of R¹², 60, winding of R¹³, 61, switch s⁵ and ground, energizing relay R¹³ which locks itself energized over the circuit B, 42, 43, armature and inner contact of relay R¹³, winding of relay R¹³, 61, s⁵ and ground. This energization of trunk-connecting relay R¹³ connects the conductors 23—24 of the trunk through to the outer contacts of the ringing relay R¹⁴ and through to the wipers s'. This furnishes a path through test relay R¹¹ as follows:—B, 42, 62, R¹¹, 63, talking conductor to left hand armature of R¹⁴, back contact and talking conductor to armature of energized relay R¹³, conductor 23, winding of relay R⁶ and ground; however, this circuit is adapted to be opened by the attraction of the armatures of relay R¹⁴ and it is the function of the connector switch that the opening of this circuit at R¹⁴ shall succeed its closing at R¹³ by a time limit so small that restoration of the connector switch is not permitted. It will be noted

in the study of this time element that the test relay R¹¹ must attain the degree of energization required to attract its armature, must swing its armature through its full travel to close its contact and that subsequently to the closure of the contact of R¹¹ the release magnet s⁶ must reach the required degree of magnetization and must overcome the inertia of its armature and move it through some definite arc before the release of the switch S will be effected. Since the circuit of the test relay R¹¹ from the wiper s' to ground through the relay R⁶ of the same connector is at best only momentarily closed, this closure being during the instant after the operation of relay R¹³ and before the operation of R¹⁴, it follows that the series of necessarily consecutive operations just traced with respect to the release magnet can not occur during this very short interval, and therefore no false test resulting in a consequent improper release occurs.

The commutator X, as has been mentioned, is carried upon the shaft which carries the number wheels and commutator devices Q⁰, Q, Q', Q², etc., and the commutator X is adjusted angularly with respect to those wheels so that the conducting portion of X is in electrical connection with its brush at the time that the energization of the relay R¹³ occurs.

It is seen that by the closing of contacts of R¹³, by which current flow through relay R¹¹ was permitted, current was simultaneously provided for through path B, 42, X, winding of R¹⁴, contact and armature r¹³, 63, 50, r¹⁴, 51 and ground. Thus current begins to flow through the winding of relay R¹⁴ at the same instant that current begins to flow through the winding of relay R¹¹, and, assuming equal speed in the operation of armatures, relay R¹⁴ will have moved its armature and will have broken its back contact, thereby cutting off current from relay R¹¹, in ample time to prevent the restoration of the switch S by operation of release magnet s⁶, the break at the armature of R¹⁴ probably occurring in time to prevent any contact whatever at the armature of relay R¹¹. Thus a test condition is maintained with the test wiper s' isolated from the winding of relay R⁶ by the break at the armature of relay R¹⁴, and the design and adjustment of the commutator X shall be such that the relay R¹⁴ is held energized throughout the maximum period occupied by generator selection impulses and until the opening of the circuit of the test relay R¹¹ by the opening of the switch 62 upon release of the armature of the solenoid R¹⁵. The armature of the solenoid R¹⁵ is sluggish and does not open the switch 62 between the generator selection impulses, so that the test circuit here described is maintained continuously during the period of generator-selection.

Leaving the various parts of apparatus in the condition now considered, we will follow the action of the apparatus in response to the generator-selection impulses. In the instance assumed, since station No. 3 is to be called three battery impulses will be received over the wire 23 operating the armature of the relay R^6 successively three times, which in turn acts over the path 47, 46, 57, R^{12} , etc., to operate the armatures of relay R^{12} in succession three times; the armature r^{12} through its front and back contacts effects the selection of the desired ringing generator as follows: Upon attraction of r^{12} by the first generator selection impulse, it makes electrical connection with its inner contact, but inasmuch as the wire 64 is open at the armature of relay R^{19} no complete circuit is closed. Upon the release of the armature r^{12} at cessation of the first generator-selection impulse, circuit is closed through elements B, 42, 43, contact of R^{13} , 60, r^{12} , 65, contact of R^{16} , winding of R^{19} and ground, energizing relay R^{19} which locks over the circuit B, 42, 43, contact of R^{13} , 60, 69, armature and contact of R^{19} , winding of R^{19} and ground. If but one generator-selection impulse were received, the generator G would remain in connection with conductor 40 ready for connection through conductor 41 to the contact of the ringing relay R^{14} . At the beginning of the second generator-selection impulse, relay R^6 is energized and armature r^{12} is attracted, closing circuit through elements B, 42, 43, contact of R^{13} , 60, r^{12} , 64, closed contact of lower armature of relay R^{19} , back contact of unenergized relay R^{20} , winding of relay R^{16} and ground, energizing relay R^{16} which then locks over the circuit B, 42, 43, contact of R^{13} , 60, 69, armature contact and winding of R^{16} . Upon the cessation of the second generator-selection impulse, the armature r^{12} is released, closing circuit over B, 42, 43, contact of R^{13} , 60, r^{12} , 65, closed contact of lower armature of energized relay R^{16} , back contact of lower armature of unenergized relay R^{17} , winding of relay R^{20} and ground, energizing relay R^{20} which then locks itself through its own contact by current received over conductor 69 to ground as in the case of relays R^{16} and R^{19} . If no more generator-selection impulses were received, the effect of the two impulses thus far followed would be to leave generator G connected to conductor 40 through contact of energized relay R^{16} , that being the proper generator for ringing the second station on a party line.

At the beginning of the third and last generator-selection impulse, the armature r^{12} is again attracted, closing circuit over elements B, 42, 43, contact of R^{13} , 60, r^{12} , 64, closed contact of energized relay R^{19} , closed inner contact of energized relay R^{20} , closed outer contact of unenergized relay R^{21} , winding of relay R^{17} and ground, energizing relay R^{17} , which then locks itself by current through its own contact and winding over conductor 69 to ground. Upon the cessation of the third and last generator-selection impulse, the armature r^{12} is released, closing circuit through elements B, 42, 43, contact of R^{13} , 60, r^{12} , 65, closed inner contacts of energized relays R^{16} and R^{17} , closed outer contact of unenergized relay R^{18} , winding of relay R^{21} and ground, energizing relay R^{21} which then locks itself by current through its own armature contact and winding from conductor 69 to ground. This leaves relays R^{16} and R^{17} energized and leaves relay R^{18} unenergized, thus effecting the connection of generator G² to the conductor 40, and as the generator-selection impulses now cease, solenoid R^{15} releases its armature, opening the circuit of the test relay R^{11} and closing the circuit between conductors 40-41, thus connecting the selected generator G² over conductor 41 to the inner contact of the left hand armature of ringing relay R^{14} and thus through the upper wiper s' and to the line conductor of the selected line to ring the third station upon the party line selected. The ringing will continue until the insulated portion of the commutator X passes under the brush of that commutator when the circuit of the winding of relay R^{14} will be interrupted and by release of that relay's armature the circuit from the wipers s' will be removed from the generator and carried to relays R^7 and R^6 respectively. The line selected will be subjected alternately to periods of ringing when the relay R^{14} is energized and to periods of non-ringing when the relay R^{14} is deenergized. Upon the answering of the called sub-station, or of any sub-station upon that party line, during a period of non-ringing, current immediately will flow through elements B, 42, winding of R^7 , 24 lower s', line conductor, substation bridge, return line conductor, upper s', 23, winding of R^6 and earth, energizing R^6 and attracting its armatures.

By the operation of the left hand armature of R^6 , circuit is closed through elements B, 42, left hand armature and inner contact of R^6 , winding of R^{19} , 54, contact and left hand armature of R^7 , 55 and ground, energizing R^{19} which then locks over the circuit B, 42, right hand armature and contact of R^{19} to winding of R^7 , 54, contact and armature of R^7 , 55 and ground. By energization of relay R^{19} , ground is taken off of wire 50 so that ringing relay R^{14} may not again be energized. Also by the energization and locking of R^{19} the relay R^6 is released and remains released throughout the remainder of the connection. This is the condition of conversation and continues until the hanging up of the telephone and the breaking of the substation bridge upon the called line.

Upon the hanging up of the telephone and the breaking of the substation bridge upon the called line, disconnection of the switch S is effected as follows: Circuit is interrupted over the return wire of the line and through relay R⁶ to ground, releasing the armatures of relay R⁶, but current continues through elements B, 42, winding of R⁷, 24, lower wiper s', and the sleeve side of the connected line and the winding of its cut-off relay M' to ground, maintaining the energization of the relay R⁷. By the release of the left hand armature of relay R⁶ a release relay circuit is established through elements B, 42, left hand armature and outer contact of deenergized relay R⁶, winding of release relay R²², inner contact and armature r¹⁰ of relay R¹⁰, 51 and ground, energizing release relay R²² which, by closing its contact, energizes release magnet s⁶, which effects immediate restoration of all parts of the switch S to the normal position of disuse.

A consideration of test conditions during the process of the connection is desirable. When the test wiper or upper wiper s' connects with the test conductor of the selected line, no action is taken either to test for busy or to place a busy test upon the line until the wheels Q', Q², Q³, etc., have in due course of progress begun to send the generator-selection impulses; at this time, by the action of the solenoid R¹⁵, the selected line is tested for busy condition, the testing for busy being continued throughout the receipt of the generator-selection impulses and the line being left unguarded against connection by other connectors; at the close of the generator-selection impulses the test relay is taken off and the ringing generator is substituted. From this time a busy test guard condition is placed upon the test conductor of the selected line, being alternately the potential of the selected ringing generator when the relay R¹⁴ is energized, which is sufficient to energize any relay R¹¹ which may test the line during the interval of ringing, and between the intervals of ringing the busy test consists of the ground circuit through the relay R⁶. If the line thus connected with be tested for busy by some other connector attempting a connection with it and during the interval of deenergization of ringing relay R¹⁴, a current will flow from the connector then testing to the test conductor of the line, thence through the test wiper of the connector of Fig. 3 holding the line, and through back contact of relay R¹⁴, front contact of R¹⁵, 23, and winding of R⁶ to ground. This current will be of sufficient strength to energize the test relay R¹¹ of the distant connector attempting to take the line being held, and this will effect disconnection of that connector but it will not be of sufficient strength to energize the relay

R⁶ inasmuch as by the energization and subsequent deenergization of that relay, the said testing current would also restore the holding connector of Fig. 3 to its normal condition of idleness.

I have thus described and stated the operation of one form of my invention. Many changes can be made therein without departing from the spirit thereof. In a prior application I have shown the same arrangement as in Fig. 2, hereof, and also a number of other arrangements of the sender circuits, any one of which could be substituted herein.

It will be observed that the circuit during conversation is the same as the standard manual talking circuit, having a single pair of condensers, C, and the main battery B bridged across each side of these condensers through a pair of relays.

Having thus described my invention what I claim is:—

1. In a telephone exchange system a plurality of subscribers' lines having answering terminals and multiple or connective terminals, signal devices associated with the answering terminals, automatic connector switches containing multiple terminals, an operator's connective circuit adapted to connect the answering terminal of a calling line with a connector switch containing the multiple-terminals of the line wanted, and locking keys associated with the connective circuit adapted to be set by the operator for the number of the line wanted, and a multiple selection-impulse generator associated with said keys and operating through said keys to furnish selective impulses for selecting and connecting with a desired line.

2. In a telephone exchange system a plurality of subscribers' lines, answering and multiple or connective-terminals for each line, automatic switches containing the multiple or connective-terminals, means controlled by an operator to connect a calling line with a given connector switch, a multiple signal sender, locking keys for selecting desired combinations of signals from said signal sender, and further means controlled by the operator to connect said keys and signal sender to the connector switch to operate said switch selectively, together with means whereby the subscriber may signal the operator when the conversation is finished.

3. In a telephone exchange system a plurality of subscribers' lines, an answering switchboard and one or more automatic switches auxiliary thereto, answering terminals for the lines, located on the switchboard, multiple or connecting terminals for the lines located in the automatic switch-banks, automatic switch-terminals located on the switchboard, means whereby the operator may connect the same with the answering terminal of a calling line when required, a multiple power-driven signal transmitting

- device, a plurality of sets of impulse selecting locking buttons whereby the operator by locking one button from each bank may so modify the signal transmitting device in 5 to so to cause a plurality of signals to be sent successively as required for the selection of a predetermined desired line, and means controlled by the operator to apply the same to an automatic switch in order to complete 10 a connection manually initiated.
4. In a telephone exchange system a plurality of subscribers' lines, an operator's manual connective apparatus with auxiliary automatic switching apparatus, means whereby connection with a calling subscriber is manually effected, the number wanted 15 communicated to the operator, and a series of rows of locking keys adapted to be set to the desired line and station number and controlled by the operator to prepare said 20 number for the auxiliary switches, together with automatic means comprising a plurality of independently and differently characterized electrical control circuits for controlling a switch in accordance with the 25 number set, and means associated with the switches to automatically signal a called line when selected.
5. In a telephone exchange system, a plurality of line circuits, means manually controlled by an operator for initiating a connection in answer to a call, a controlling device, consisting of a continuously revolving commutator device and a plurality of rows 30 of locking number keys adapted to be set in accordance with the number wanted, and automatic means brought into operation by said controlling device and actuated in accordance with the number set to complete 35 the connection.
6. In a telephone exchange system a plurality of line-circuits, and means for interconnecting the same comprising the following instrumentalities: manual initiating or 40 answering terminals, a number setting device, said number setting device consisting of a plurality of continuously revolving commutators and locking number keys, automatic switches controlled by said number 45 setting device and acting in conjunction with the manual initiating apparatus to complete any desired connection, and automatic means for ringing the called subscriber.
7. In a telephone exchange system a plurality of line-circuits and means for interconnecting the same comprising the following instrumentalities: manual initiating or 50 answering terminals, a number setting device, consisting of a constantly driven impulse 55 sender and a set of locking impulse-selecting number keys, automatic switches controlled by said number setting device and acting in conjunction with the manual initiating apparatus to complete any desired connection, and automatic means for ringing the called subscriber, said means being brought into action upon the completion of the connection by the automatic switch.
8. In a telephone exchange system a plurality of line-circuits, and means for interconnecting the same comprising the following instrumentalities: manual initiating or 60 answering terminals, a number setting device, consisting of a constantly driven impulse sender and a set of locking impulse-selecting number keys, automatic switches controlled by said number setting device and acting in conjunction with the manual initiating apparatus to complete any desired connection, and automatic means for ringing the called subscriber, said means being brought into action upon the completion of the connection by the automatic switch and automatically rendered inoperative when the called subscriber answers.
9. In a telephone exchange system a plurality of subscribers' lines, a manual switchboard containing answering terminals for said lines and call signals associated therewith, auxiliary automatic switches containing multiple or connecting terminals of said lines and having trunks terminating on said switchboard, with means whereby an operator may connect a switch-trunk with a calling line terminal, a signal controlling device on said switchboard adapted to be set by the operator for any desired number, a power-driven impulse transmitter having definite signal periods, means for bringing said transmitter into operative connection with a selected switch-trunk at the beginning of a signal period to transmit impulses so as to work the automatic switch in accordance with the number set by the operator, and means to cut off said impulse transmitter at the termination of the signal period.
10. In a telephone system, the combination of subscriber's lines, calling jacks and signals for said lines, automatic connector switches in which multiples of said lines appear, trunks extending to said automatic switches, manual means for connecting a calling line to one of said trunks, and an impulse sending device comprising a key board associated with each trunk together with automatic means to determine the connection and disconnection of said key board from the trunk for controlling the movements of the automatic switch of said trunk, to connect the trunk to the terminals of a desired line.
11. In a telephone system, the combination of subscriber's lines, calling jacks and signals for said lines, automatic connector switches in which multiples of said lines appear, trunks to said automatic switches, manual means for connecting a calling line to one of said trunks, and a constantly-driven signal sending device with locking

- signal-selecting keys for controlling the movements of the automatic switch of said trunk throughout a plurality of successive directory digits to connect the trunk to the 5 terminals of a desired line.
12. In a telephone system, the combination of subscriber's lines, a calling jack and signal for each of said lines, automatic connector switches in which multiples of said 10 lines appear, trunks to said automatic switches, manual means for connecting a calling line to one of said trunks, and a constantly driven multiple-signal-sending device for controlling the movements of the 15 automatic switch associated with said trunk to connect said trunk to the terminals of a desired line.
13. In a telephone system, the combination of subscriber's lines, a calling jack and 20 signal for each of said lines, automatic connector switches in which multiples of said lines appear, trunks to said automatic switches, manual means for connecting a calling line through one of said trunks to 25 one of said automatic switches, and a constantly driven multiple-signal-sending device with locking selecting number keys for controlling the movements of said automatic switch throughout a plurality of successive 30 directory digits to connect its trunk to the terminals of a desired line.
14. In a telephone system, the combination of subscriber's lines, a calling jack and signal for each of said lines, automatic connector switches in which multiples of said 35 lines appear, trunks to said automatic switches, cord pairs for connecting a calling line with a trunk to one of said automatic switches, a constantly driven signal-sending 40 device, and locking signal-selecting keys associated with said cord pairs for controlling the movements of said automatic switch to connect its trunk to the terminals of a desired line.
15. In a telephone system, the combination of subscriber's lines, a calling jack and signal for each of said lines, automatic connector switches in which multiples of said 45 lines appear, trunks to said automatic switches, a constantly driven multiple-signal-sending 50 device, cord pairs for connecting a calling line to a trunk to an automatic switch, and sets of locking signal-selecting keys for each of said cord pairs whereby 55 said automatic switch may be controlled throughout a plurality of successive directory digits to connect its trunk to the terminals of a desired line.
16. In a telephone exchange system, a plurality of subscribers' lines; an operator's 60 manual connective apparatus with auxiliary automatic switching apparatus, said auxiliary automatic switching apparatus being divided into groups corresponding to groups 65 of subscribers' lines; means whereby con-
- nection with a calling subscriber is manually effected and the number wanted communicated to the operator; means whereby the operator manually selects the group of automatic switching apparatus corresponding to 70 the number of the subscriber wanted; a mechanical number-recording device whereon the operator may record the digits of the number of the line desired, supplemental to the directory digits provided for by proper 75 selection of the groups of automatic switches; automatic means whereby the mechanically recorded directory number is translated into corresponding controlling impulses whereby the selected automatic 80 switch is controlled to complete the connection of the calling telephone line with the line desired; and further means whereby the desired station upon a selected-party line is selectively operated, substantially as, de- 85 scribed.
17. In a telephone exchange system, a plurality of subscribers' lines; an automatic switching apparatus, manual connective apparatus whereby connection may be made 90 between a calling line and said automatic switching apparatus; a system of continuously revolving commutators producing in each revolution a complete cycle of selective impulses and locking keys adapted to ex- 95cerpt from any cycle the specific impulses required for a specific selection; and automatic means for applying the excerpted impulses to the connected automatic switch for the selection of the desired line, substan- 100 tially as described.
18. In a telephone exchange system, a plurality of subscribers' lines; an automatic switching apparatus; manual connective apparatus; whereby connection may be made 105 between a calling line and said automatic switching apparatus; a system of continuously revolving commutators producing in each revolution a complete cycle of selective impulses and locking keys adapted to ex- 110cerpt from any cycle the specific impulses required for a specific selection; automatic means for applying the excerpted impulses to the connected automatic switch for the selection of the desired line; and further 115 means for ringing selectively a station upon the selected line, substantially as described.
19. In a telephone exchange system, a plurality of subscribers' lines; automatic connector switches; manual switching apparatus 120 for connecting a calling line to a connector switch; a mechanical number-recording device; a constantly driven signal-sending device adapted to send multiple signals in repeated cycles; and means whereby said signal-sending device may be connected to the automatic switch at the beginning of a cycle, may be permitted to send signals in accordance with the number recorded upon the number-recording device, and may be discon- 125 130

nected from said automatic switch at the end of the cycle, substantially as described.

20. In a telephone exchange system, a plurality of subscribers' lines; automatic connector switches; manual switching apparatus for connecting a calling line to a connector switch; a mechanical number-recording device; a constantly driven signal-sending device adapted to send multiple signals in repeated cycles; and automatic means whereby said signal-sending device may be connected to the automatic switch at the beginning of a cycle, may be permitted to send signals in accordance with the number recorded upon the number-recording device, and may be disconnected from said automatic switch at the end of the cycle, substantially as described.

21. In a telephone exchange system, a plurality of line circuits, automatic switching apparatus for interconnecting the same, manual means for initiating a connection, means controlled by an operator through the automatic switches to complete it, and means controlled by the called subscriber for disconnection, substantially as described.

22. In a telephone system, the combination of subscribers' lines, an answering jack and a calling signal for each of said lines, automatic connector switches in which multiples of said lines appear, trunks from a manual position to said automatic switches, cord pairs adapted to connect with said trunks, and a constantly-driven signal sending device with keys and locking signal selecting circuits for controlling the movements of an automatic switch to connect its trunk to a desired line, substantially as described.

23. In a telephone system, the combination of subscriber's lines, circuits and equipment manually operated for answering said lines, automatic connector switches in which multiples of said lines appear, trunks from the manual answering position to said automatic switches, and a constantly driven signal - sending device, with signal - selecting keys and locking circuits associated with said manual answering equipment and adapted to control the selector switch of a connected trunk to connect its trunk with a desired line, substantially as described.

24. In a telephone system, the combination of subscriber's lines terminating in answering jacks; automatic connector switches in which multiples of said lines appear; trunks connecting said automatic connector switches to jacks adjacent to the answering jacks of said lines; cord pairs adapted to connect line jacks and trunk jacks, and a constantly driven signal sending device with signal selecting number keys for controlling the movement of said automatic switches to connect the trunks to the terminals of desired lines, substantially as described.

25. In a telephone system, the combination of subscriber's lines terminating in answering jacks; automatic connector switches in which multiples of said lines appear; trunks connecting said connector switches to jacks adjacent to the jacks of said lines; cord pairs adapted to connect line jacks and trunk jacks; a constantly driven signal-sending device; and sets of locking signal-selecting keys associated with each cord pair for selecting from said signal-sending device desired signal impulses for controlling the connector switch of a selected and connected trunk to connect its trunk with the terminals of a desired line, substantially as described.

26. In a telephone system, the combination of subscriber's lines terminating in answering jack; automatic connector switches in which multiples of said lines appear; trunks connecting said automatic switches to jacks adjacent to the answering jacks of said lines; cord pairs adapted to connect line jacks and trunk jacks; a constantly driven signal-sending device; and sets of signal-selecting keys with locking circuits and associated with each cord pair for selecting from said signal-sending device desired signal impulses for controlling the connector switch of a selected and connected trunk to connect its trunk with the terminals of a desired line; substantially as described.

27. In a telephone system, the combination of subscriber's lines, calling jacks and signals for said lines, automatic connector switches in which multiples of said lines appear, manual means for connecting a calling line to one of said automatic switches, and a constantly driven signal-sending device with selecting number keys for controlling the movements of said automatic switch throughout a plurality of successive directory digits to connect the manually connected calling line to the terminals of a desired line.

28. In a telephone system, the combination of subscriber's lines, calling jacks and signals for said lines, automatic connector switches in which multiples of said lines appear, manual means for connecting a calling line to one of said automatic switches, and a multiple signal sending device with selecting number keys for controlling the movements of said automatic switch throughout a plurality of successive directory digits to connect the manually connected calling line to the terminals of a desired line.

29. In a telephone system, the combination of subscriber's lines, calling jacks and signals for said lines, automatic connector switches in which multiples of said lines appear, manual means for connecting a calling line to one of said automatic switches, and a constantly driven multiple signal

- sending device with selecting number keys for controlling the movements of said automatic switch throughout a plurality of successive directory digits to connect the manually connected calling line with the terminals of a selected line.
30. In a telephone system, the combination of subscriber's lines, calling jacks and signals for said lines, automatic connector switches in which multiples of said lines appear, manual means for connecting a calling line to one of said automatic switches, and a constantly driven signal sending device with selecting number devices for controlling the movements of said automatic switch to connect the manually connected calling line with the terminals of a desired line.
31. In a telephone system, the combination of subscriber's lines, calling jacks and signals for said lines, automatic connector switches in which multiples of said lines appear, manual means for connecting a calling line to one of said automatic switches, and a multiple signal sending device with locking selecting number keys for controlling the movements of said automatic switch to connect the manually connected calling line with the terminals of a desired line.
32. In a telephone system, the combination of subscriber's lines, calling jacks and signals for said lines, automatic connector switches in which multiples of said lines appear, manual means for connecting a calling line to one of said automatic switches, and a multiple signal sending device with selecting number devices for controlling the movements of said automatic switch to connect the manually connected calling line with the terminals of a desired line.
33. In a telephone system, the combination of subscriber's lines, calling jacks and signals for said lines, automatic connector switches in which multiples of said lines appear, manual means for connecting a calling line to one of said automatic switches, and a constantly driven multiple signal sending device with locking selecting number keys for controlling the movements of said automatic switch throughout a plurality of successive directory digits to connect the manually connected calling line with the terminals of a desired line.
34. In a telephone system, the combination of subscriber's lines, calling jacks and signals for said lines, automatic connector switches in which multiples of said lines appear, manual means for connecting a calling line to one of said automatic switches, and a constantly driven multiple signal sending device with selecting number devices for controlling the movements of said automatic switch throughout a plurality of successive directory digits to connect the manually connected calling line to the terminals of a desired line.

35. In a telephone system, the combination of subscriber's lines, calling jacks and signals for said lines, automatic connector switches in which multiples of said lines appear, manual means for connecting a calling line to one of said automatic switches, and a constantly driven signal-sending device with locking selecting number devices for controlling the movements of said automatic switch throughout a plurality of successive directory digits to connect the manually connected calling line with the terminals of a desired line.

36. In a telephone system, the combination of subscriber's lines, calling jacks and signals for said lines, automatic connector switches in which multiples of said lines appear, manual means for connecting a calling line to one of said automatic switches, and a multiple signal sending device with locking selecting number devices for controlling the movements of said automatic switch throughout a plurality of successive directory digits to connect the manually connected calling line to the terminals of a desired line.

37. In a telephone system, the combination of subscriber's lines, calling jacks and signals for said lines, automatic connector switches in which multiples of said lines appear, manual means for connecting a calling line to one of said automatic switches, and a constantly driven multiple signal sending device with locking signal selecting devices for controlling the movements of said automatic switch throughout a plurality of successive directory digits to connect the calling line with the terminals of a desired line.

38. In a telephone system, the combination of subscriber's lines, calling jacks and signals for said lines, automatic connector switches in which multiples of said lines appear, cord pairs for connecting a calling line with one of said automatic connector switches, a constantly driven signal-sending device, and signal selecting keys associated with said cord pairs for controlling the movements of said automatic switch to connect the calling line to the terminals of a desired line.

39. In a telephone system, the combination of subscriber's lines, calling jacks and signals for said lines, automatic connector switches in which multiples of said lines appear, cord pairs for connecting a calling line with one of said automatic connector switches, a constantly driven signal-sending device, and locking signal-selecting keys associated with said cord pairs for controlling the movements of said automatic switch to connect the calling line to the terminals of a desired line.

40. In a telephone system, the combination of subscriber's lines, calling jacks and signals for said lines, automatic connector

- switches in which multiples of said lines appear, cord pairs for connecting a calling line with one of said automatic connector switches, a constantly driven signal-sending device, and signal-selecting devices associated with said cord pairs for controlling the movements of said automatic switch to connect the calling line to the terminals of a desired line.
41. In a telephone system, the combination of subscriber's lines, calling jacks and signals for said lines, automatic connector switches in which multiples of said lines appear, cord pairs for connecting a calling line with one of said automatic connector switches, a signal-sending device, and individually operable independently characterized interlocking signal-selecting devices associated with said cord pairs for controlling the movements of said automatic switch to connect the calling line to the terminals of a desired line.
42. In a telephone system, the combination of subscriber's lines, calling jacks and signals for said lines, automatic connector switches in which multiples of said lines appear, cord pairs for connecting a calling line with one of said automatic connector switches, a constantly driven signal-sending device, and locking signal-selecting devices associated with said cord pairs for controlling the movements of said automatic switch to connect the calling line with the terminals of a desired line.
43. In a telephone system, the combination of subscriber's lines, a calling jack and signal for each of said lines, automatic connector switches in which multiples of said lines appear, manual means for connecting a calling line to one of said automatic switches, and a constantly driven signal-sending device with locking signal-selecting keys for controlling the movements of said automatic switch to connect the calling line with which it is manually connected to the terminals of a desired line.
44. In a telephone system, an operator's connecting devices, an impulse generating device delivering impulses of varying characteristics, bus wires leading to said operator's connecting devices, contact pairs associated with said bus-wires, auxiliary conductors extending from said generating device to said contact pairs, and keys for controlling the connection of said bus wires to said auxiliary conductors.
45. In a telephone system, an operator's connecting devices, an impulse generating device delivering impulses of varying characteristics, bus wires leading to said operator's connecting devices, contact pairs associated with said bus-wires, auxiliary conductors extending from said generating device to said contact pairs, and locking keys for controlling the connection of said bus wires to said auxiliary conductors.
46. In a telephone system, an operator's connecting devices, an impulse generating device delivering impulses of varying characteristics, bus wires leading to said operator's connecting devices, contact pairs associated with said bus-wires, auxiliary conductors extending from said generating device to said contact pairs, and devices for controlling the connections of said bus wires to said auxiliary conductors.
47. In a telephone system, an operator's connecting devices, an impulse generating device delivering impulses of varying characteristics, bus wires leading to said operator's connecting devices, contact pairs associated with said bus-wires, auxiliary conductors extending from said generating device to said contact pairs, and locking devices for controlling the connection of said bus wires to said auxiliary conductors.
48. In a telephone system, an operator's connecting devices, an ir pulse generating device delivering impulses of varying characteristics, bus wires leading to said operator's connecting devices, contact pairs associated with said bus-wires, auxiliary conductors extending from said generating device to said contact pairs, and signal-selecting keys manually controlled by the operator for controlling the connection of said bus wire to selected ones of said auxiliary conductors.
49. In a telephone system, the combination of subscriber's lines terminating in answering jacks, automatic connector switches in which multiples of said lines appear, trunks connecting said automatic switches to jacks adjacent to the answering jacks of said lines; cord pairs adapted to connect line jacks and trunk jacks, a power driven signal sending device, and sets of individually operable independently characterized signal selecting keys with locking circuits through which they may be connected with each cord pair for selecting from said signal sending device desired signal impulses for controlling the connector switch of a selected and connected trunk to connect its trunk with the terminals of a desired line.
- In testimony whereof I have affixed my signature in presence of two witnesses.
- EDWARD E. CLEMENT.
- Witnesses:
- JAMES H. MARR,
E. ELTONSTON, Jr.
